FURNACE HEARTH

Beverly K. Walpole, Cranston, R.I., assignor to National Furnace Corporation, a corporation of Rhode Island

Filed Mar. 26, 1956, Ser. No. 574,028

4 Claims. (Cl. 263—21)

This invention relates to improvements in a hearth for a furnace employed for heat treating material, particularly a hearth for a furnace of the continuous operation type in which the work is fed in at one end, advanced through the furnace, and discharged from the other end.

In furnaces of the above type the work is loaded on the hearth at one end thereof, and by vibrating the hearth or advancing and suddenly stopping the hearth, the work is made to move to the other end thereof. The furnace is operated in a continuous manner, and the work is loaded on a platform joining the hearth, or a continuation of the hearth. The work is moved along the platform on to the hearth and as it enters the furnace is relatively cold. This causes large heat differentials of the hearth for a substantial distance within the furnace causing great thermal shocks and contraction and expansion of the hearth, which results in conditions causing the hearth to have a relatively short life.

Hearths of the above character are usually a one-piece structure, and the surface along which the work is moved must be maintained smooth and free of obstructions to the movement of the work. The hearths are relatively thick and heavy, and when it becomes necessary to withdraw the same from the furnace for repair, as by way of example, to free the surface of work particles which are more or less welded thereto, considerable time is spent in waiting for the hearth to cool to permit working thereon and likewise waiting for the furnace to cool so as to return and mount the hearth within the furnace, and much labor is involved pulling the hearth out of the furnace. A hearth of the length required being subjected to different temperatures cannot expand evenly and thus becomes buckled along portions thereof where the widely varying temperatures occur.

An object of the invention is to improve generally on hearths for furnaces of the above character.

Another object of the invention is to provide a hearth so constructed as to be readily removed from the furnace.

Another object of the invention is to provide a hearth constructed of sections so as to permit easy removal and replacement of a damaged part thereof.

Another object of the invention is to provide a hearth so constructed as to be supported and actuated on the existing hearth of a furnace.

A more specific object of the invention is to provide a hearth having work engaging surfaces composed of short replaceable units, each independently expandable without exerting strain on other units of the hearth.

Another object of the invention is to provide my hearth over that usually employed, causing it to be a sub-hearth of my improved furnace.

With these and other objects in view, the invention consists of certain novel features of construction as will be more fully described and particularly pointed out in the appended claims.

In the accompanying drawings:

Figure 1 is a plan view of my improved hearth shown connected to a portion of a hearth vibrating mechanism;

2

Figure 2 is a plan view of the frame of the hearth;

Figure 3 is a longitudinal sectional view of a fragmentary portion of the frame of Figure 2 taken substantially along line 3—3 of Figure 2 and shown on a larger scale;

Figure 4 is a sectional view taken substantially along line 4—4 of Figure 3;

Figure 5 is a sectional view taken along line 5—5 of Figure 1 shown on a larger scale and showing the sub-hearth and the support for the hearth which was omitted in Figure 1;

Figure 6 is a lateral sectional view taken along line 6—6 of Figure 5 but with the roller mechanism shown in Figure 5 omitted;

Figure 7 is a plan view of the sub-hearth omitted from Figure 1;

Figure 8 is an elevational view of the sub-hearth shown in Figure 7;

Figure 9 is a plan view of a single unit of the hearth;

Figure 10 is a sectional view of a portion of a hearth unit taken substantially along line 10—10 of Figure 9.

The hearth 14 (Figure 1) according to the embodiment illustrated comprises an open frame 15 (see Figure 2) having sides 16 which are made of cylindrical stock and secured to each other by a plurality of equally spaced cross members 17 which are also cylindrical in cross section. The members 17 are similar, and the end portions are turned at right angles as at 18 and extend along the inner surface of sides 16 and are there welded in place. A second cross member 19 is positioned adjacent each member 17 in spaced relation therewith. The member 19 is made of flat material generally rectangular in cross section, and the ends abut against the sides 16 and there welded in place. These cross members 19 are of a width equal to the diameter of the sides 16 and are related thereto to extend across from one side 16 to the other side 16 tangentially to the top and bottom thereof.

The frame is additionally reinforced by longitudinal members 20 which extend from a cross member 17 to a cross member 19. As best seen in Figure 3, each member 20 is made of flat stock and extends edgewise with the ends thereof abutting against cross members 17 and 19 and there welded in position. The member 20 extends from member 19 at a slight angle upwardly from the plane of the frame, as seen in Figure 3, and is tapered as at 21, forming an edge support 22 which is slightly inclined to a plane extending tangentially from the sides 16. There are two rows of these members or stringers 20 spaced from the sides, as seen in Figure 3, with each member 20 in a row extending lengthwise of the frame.

The portion of the frame so far described, which extends to the left of the cross member 17' and including this member 17', is made of a high heat resistance material known in the art, as by way of example, high nickel chrome alloy steel. This portion of the frame 15 is adapted to be positioned within the furnace (not shown).

The portion to the right of cross member 17' does not enter the furnace, and for the sake of economy of manufacture, the portion of the frame which extends to the right of the cross member 17' and which includes the sides 16', cross member 17'', and longitudinal members 20' is made of a steel less resistant to heat and thus less expensive. The sides 16' are secured to the sides 16 as at 23 by means of a weld joint. The free ends of the sides 16' are provided with screw threads 24 for a purpose which will hereinafter appear.

The work holding surface or floor 14 of the hearth comprises a plurality of separate units 30 which are laid along the frame 15 with the adjacent end portions of the units overlapping each other in the manner of shingles. Each unit 30 extending to the left of cross

member 17' is similar to the other and comprises a sheet metal tray-like body (see Figure 9) having a floor 31 and side flanges 32 which extend at substantially right angles to the floor 31. One end of the tray is provided with a lip 33 which is of less width than the floor 31, as shown. The lip 33 extends downwardly at an acute angle to the vertical with the end portion 33' thereof turned outwardly at substantially 90° and thus forms an L-shaped projection or hook depending from the floor 31 at the rear end thereof. The unit 30 is made wider at the rear and tapered to the forward end for a purpose which will hereinafter appear.

As best seen in Figures 5 and 6, each unit 30 is detachably secured to the frame by passing the lip 33 in the space between adjacent members 17, 19 and hooking the turned end portion thereof beneath the member 17. As previously described, the units 30 are made wider at the rear end thereof and so dimensioned that the forward end of each unit 30 will be received in nested relation within the rear end of an adjacent unit and in overlapping relation therewith in a shingle-like fashion. Thus, the weight of each unit in addition to the weight of the work serves to retain each unit in place. It will be seen in these two Figures 5 and 6 that the floor 31 of each unit 30 rests at some point on the side members 16. It will also be seen that the said floor rests on the edges 22 of the longitudinal stringers 20, which edges extend in the plane of the floor of the next in line unit, so that the entire floor of each unit is supported substantially its entire length although overlapping adjacent unit. Bent portions of sheet metal during expansion tend to return to position before bending; that is, the tendency of the bent portions is to straighten out. It will be apparent that such tendency will move the lip 33 against the member 17 which thus will check any further tendency of the lip to straighten. The units 30 (see Figure 1) provide the floor of the hearth from the location of cross member 17' to the discharge end of the hearth. A unit 30' is similar to unit 30 with the exception that it is made longer and extends from the cross member 17" to overlap the unit 30 which is hooked to the cross member 17'. The unit or pan 30' likewise rests on longitudinal members or stringers 20' which are similar to stringer 20 with the exception that these stringers 20' are made of a steel less resistant to heat.

In order to assure the position of units 30 in nested relation, each unit 30 at the overlapping end is provided with an opening 34 (see Figure 5) through the flanges 32 thereof. The opening in one flange will be positioned in register with an opening in the adjacent flange, and a pin or the like 35 is inserted in the said registered opening and is welded to the outer of said flanges as at 36 (see Figure 5). The pin is made flush with the inner side of the inner flange 32 so as to eliminate any obstruction to the smooth flow of work along the hearth. When it becomes necessary to replace a damaged unit 30, the pin 35 may be removed by applying a hammer or like blow to the inner side of the pin to remove the same so as to free the damaged unit.

The hearth 14 above described may be made part of any of various hardening furnaces to which the hearth may be adapted. It is, however, one aspect of the present invention to use the hearth 14 with furnaces of the above type and to employ the existing hearth thereof for a support for the hearth 14 and to modify the vibrating mechanism thereof in a manner to adapt the same for vibrating the hearth 14. In Figures 7 and 8 I have illustrated at 37 that which formerly was the hearth in common use in furnaces of the above type along which the work is advanced by known mechanism. This former hearth now becomes sub-hearth 37 and is a generally rectangular plate which is corrugated or undulated in cross section (see Figure 6) providing longitudinal troughs 38 extending from one end of the sub-hearth to the other and a multiplicity of spaced raised areas 37'

engaging the frame at spaced intervals so that a minimum of heat is transmitted to the sub-hearth. The rear or right end of the sub-hearth 37, as seen in Figure 8, has a depending flange 39 which provides for connecting the sub-hearth to a work loading table or platform 40 which has side flanges 41. The flanges 41 are continued to depend below the floor 42 and provide tracks 43. A flange 44 depends from the floor 42 against which the flanges 38 abut. Bolts 45 extend through flanges 38 and 44 which secure the sub-hearth 37 to the platform 40. The sub-hearth 37 proper is mounted on free rollers 46 (see Figure 5) which extend laterally beneath the sub-hearth 37 and are held captive in bearings 47 which are attached to the brick bed 48 of the furnace. Thus, the sub-hearth 37 is mounted for reciprocating motion; that is, the sub-hearth may be moved longitudinally thereof first in one direction and then in the other. The platform is likewise mounted for reciprocating motion by means of rollers 49 (see Figure 1) on which the tracks 43 rest. The rollers are mounted on shafts 50 which are journaled in pillow blocks 51 secured on the frame of a hearth vibrating mechanism indicated generally 52. The elements of the vibrating mechanism are not shown, in that the specific type of vibrating mechanism is not the subject of the present invention, it being understood that the mechanism indicated generally 52 is intended to be representative of any suitable type which operates to move the hearth and sub-hearth in the forward direction against an abutment to stop the hearth with a sudden jerk followed by a return to standing position for a repeated operation in response to the well-known principle of inertia to move the work relatively forward along the hearth.

In order to adapt the existing mechanism of the furnace for use with the hearth of the present invention, a support 53 in the form of a cross bar is secured to the right end edge portion of the platform 40, and this support 53 is slotted inwardly from the upper edge as at 54. The threaded end portions 24 are received in said slots 53 and secured to said support by clamp nuts 55. The frame 15 lies on the floor 42 of the platform and on the sub-hearth 37 which now becomes a support for hearth 14. The free end portion of the frame 15 is provided with lugs 56 (see Figures 2, 4, and 6) which are in the form of short cylinders attached to the sides 16 at a location to engage along the walls 38' of the outer troughs of the sub-hearth 37. Thus, the lugs 56 and the securing means at the forward end of the frame prevent lateral shifting of the hearth 14 on the sub-hearth 37. It will be apparent that vibrating motion imparted to the platform 40 will be transmitted to the sub-hearth 37 and hearth 14.

It will be apparent from the above description that the structure of the hearth 14 provides for a relatively light weight hearth which lends itself to be readily handled when necessary for repair or replacement of a unit 30. All that is necessary in order to pull the hearth from the furnace is to loosen the clamp nuts 55 sufficiently to permit removal of the frame portions 24 from the notches 54. This trailing end of the hearth may be now raised to a height to position beneath this raised end some improvised support, as for example, a bar or roller. Then by the use of a pair of tongs and/or the like, the hearth may be slid along the said improvised support relative to the sub-hearth and withdrawn from the furnace a distance sufficient to expose the unit to be replaced. The construction permits a relatively quick cooling of the exposed units and by detaching the unit to be replaced as previously described and replacing the same with another unit, the hearth may be returned in position by merely pushing the frame and units 30 in place and then turning the clamping nuts to secure the hearth to the platform 40, all this without disturbing the sub-hearth 37 from its mounting.

I claim:

1. In a furnace for heat treating material having open-

ings for the continuous passage of material therethrough, a substantially horizontal hearth comprising a frame having pairs of crossbars, a plurality of plates having fixed and free ends with their free ends overlapping the fixed ends of the next plate in shingle like fashion to permit free longitudinal expansion thereof, each plate provided with a generally Z-shape lip at its fixed ends extending over one of the pair of bars and beneath the other of said pair of bars and which may be moved to and from secured position only with the free end of the plate lifted away from the frame a substantial distance.

2. A furnace according to claim 1 wherein said plurality of pairs of cross bars are spaced from each other a distance less than the length of one of said plates.

3. A furnace according to claim 1 and longitudinally 15 extending stringer members extending between said cross bars in the space between said pairs of cross bars and on which said plates rest.

4. In a furnace for heat treating material having openings for the continuous passage of material therethrough, a substantially horizontal hearth comprising a frame having crossbars, a plurality of plates, means individually 20

securing one end of each of said plates to said frame with the other end free and overlapping the secured end of the next plate in shingle like fashion to permit free longitudinal expansion thereof, said securing means including lips on said plates extending to a location vertically beneath said crossbars, whereby said secured end is locked against being lifted in a direction substantially vertically from said frame and a sub-hearth of undulating form having crests and valleys positioned below the said first hearth with the crest engaging the first hearth at a multiplicity of spaced locations distributed over the entire area of the frame for movement therewith.
